UNITED STATES PATENT OFFICE.

PAUL R. HEYGEL, OF MORSEMORE, NEW JERSEY, ASSIGNOR TO HARRY H. STRAUS,
OF NEW YORK, N. Y.

CIGARETTE CONTAINER.

Application filed November 28, 1923. Serial No. 677,356.

To all whom it may concern:

Be it known that I, PAUL ROBERT HEYGEL, a citizen of the Republic of Germany, residing at Morsemere, county of Bergen, State 5 of New Jersey, have invented certain new and useful Improvements in Cigarette Containers, of which the following is a specification.

This invention relates to containers for 10 packaged cigarettes.

An object of the invention is to provide a container for cigarettes contained in wrappers or other original forms of package of paper or other relatively pliable material, 15 whereby the packaged cigarettes when inserted in the container are protected against injury and presented for ready removal of the cigarettes.

A further object of the invention is to 20 provide a container so arranged relative to the wrapper whereby an opening in a corner or other portion of the wrapper may be readily torn by coaction with the edge or other part of the container to form an opening 25 for removal of the cigarettes.

Further features and objects of the invention will be more fully understood from the following detail description and the accompanying drawings, in which

30 Fig. 1 is a top perspective view showing an embodiment of the invention and illustrating a manner of tearing a corner opening in the cigarette package;

Fig. 2 is a top perspective view of the container per se as shown in Fig. 1;

Fig. 3 is a sectional elevation on line 3—3 of Fig. 1; and

40 Fig. 4 is a top perspective view of a modified form of container and showing a package from which some of the cigarettes have been removed.

Referring to the drawings, the container 10 may be formed of imperforate sides 11, 12 and ends 13, 14 and have an imperforate bottom 15, but which may be varied as desired. The top of the container 10 is open or provided with an opening for receiving a pouch or other packages 16 of cigarettes 17. The inner dimensions of the sides 11, 12, ends 13, 14, are preferably such as to snugly receive and frictionally retain the package 16 of cigarettes.

At the upper edge of the container 10 is provided suitable means for facilitating the removal of a portion of the wrapper of the

cigarette package 16, and preferably to form a corner opening 18, see Fig. 1. As one such arrangement, the upper edge of the side 11 is depressed as is indicated at 19, as of a curved formation, and the upper edge of the end 13 depressed as indicated at 20 as in a similarly curved manner, whereby the joint edges 19, 20 form an effectual cutting edge and a guide for tearing away the corner portion 21, see Fig. 1, as by manual 65 grasping the paper of the wrapper 16, say with the right hand, as indicated at 22, and tearing the paper with the left hand as indicated at 23. The forming of such opening 18 may be started by grasping say with 70 the left hand the revenue stamp usually applied over the fold of the paper at the top of the package or pouch 16 and continuing the tear of the paper as aforesaid. 75 The outline of the corner opening 18 in the wrapper 16 is clean, and thus affords unobstructed removal of cigarettes at all times and obtains neatness in appearance.

By such provision of means, a corner opening is readily formed when the package 16 of cigarettes is enclosed in the container 10, and the cigarette wrapper is preserved substantially in its original condition.

80 The container may be made of imperforate material, such as cardboard, fibreboard or superposed layers of paper stock such as chipboard with appropriate exterior finishing liners, or may be made of translucent or transparent or semi-transparent material, of molded or other shaped character such as compositions, metals and the like.

85 If desired, an opening 24, see Fig. 4, may be in a side, say the side 11, to permit the markings on the cigarette package 16 to be visible when the package is enclosed in the container, or one or more additional sides may be provided with transparent or other so-called window material for like purpose as the opening 24.

100 After a corner opening has been formed in the original package 16, as described hereinabove, the container 10 protects the cigarettes from external pressure such as when the container with the cigarette package is placed in a garment pocket or in a valise or the like. The remaining cigarettes, see 25, 105 see Fig. 4, are preserved from crushing and effectively held from undue shaking. It 110 will be noted, as is indicated in Fig. 4, that

the original form of the cigarette package 16 is preserved by the container 10 notwithstanding that a portion of the wrapper has been torn away and a number of the cigarettes removed.

Whereas I have described my invention with reference to specific forms thereof, it will be understood that many changes and modifications may be made without departing 10 from the spirit of the invention.

I claim.

1. A container for original cigarette packages formed of relatively yielding material, said container comprising side, end and bottom portions of relatively stiff material, the top of said container being open and formed at one corner of the top with a depressed edge portion, said edge portion conforming to and serving as a guide for severing the desired opening to be formed in the package wrapper.

2. A container for paper wrapped packages of cigarettes, said container comprising

side, end and bottom portions of relatively stiff material, the top of the container being 25 open and formed at one corner of the top with a downwardly extending edge conforming to the desired opening in the paper wrapping of the cigarette package, said edge serving as a guide for severing the paper of 30 the cigarette package.

3. A container for original cigarette packages formed of non-self-sustaining material, said container comprising side and end portions of self-sustaining material, said container being provided with an opening for receiving such package, the edge of the opening of said container at one corner being curved transversely to the adjacent portions of the edge to serve as a guide for 40 severing the material of the original package to form the desired opening therein.

In testimony whereof I have signed this specification this 26th day of November, 1923.

PAUL R. HEYGEL.
